UNITED STATES PATENT OFFICE

LUCIEN HAYART, OF LYON, FRANCE

COMPRESSOR

Application filed May 31, 1928, Serial No. 281,832, and in France June 17, 1927.

This invention relates to an improvement made in the construction of compressors and consists in giving to the piston a double movement—that of reciprocation and of oscillation.

This piston executes in fact a reciprocating movement in a pump body, whilst the body and piston oscillate about a spindle in the interior of a shell constituting the frame. The different phases of the operation are the result of the variation of volume which the said movements produce between the piston and the pump body, on the one hand, and the block and the walls of the shell, on the other hand.

The piston of constant length is perfectly balanced at either side of the machine.

The accompanying drawing shows by way of example a construction of a compressor with a horizontal axis, built according to the invention.

Figure 1 is a cross section through the axis of rotation of the piston and pump body.

Figure 2 is a longitudinal section showing, respectively in full lines and in dotted lines, the piston at the two ends of its reciprocating motion.

Figures 3 and 4 correspond to intermediate phases of operation.

At 1 is shown the pump body in which travels the piston 2 driven by the rotation of a spindle 3. To that end, to the latter is keyed eccentrically a cylindrical part 4 which moves in the oblong opening of a cage 5 provided in the piston 2. The pump body 1 can oscillate about a spindle 6.

It will readily be understood that the rotation of the spindle 3, by causing the eccentric 4 to roll in the interior of the cage 5, will produce a reciprocating movement of the piston 2 in the body 1, whilst at the same time the whole of the piston and of the pump body will oscillate about the spindle 6.

The elements described in the foregoing are enclosed in the interior of a frame or shell 7, the side plates of the frame 7, 8 of which form bearings for the spindle 3. In the said side plates there are provided one or more openings 9 intended for the admission of air or other fluid which enters the interior of the

shell or casing. On the other hand, ports 10 provided in the walls of the lateral plates 8, enable air to enter the pump body when the movement of the piston which itself acts as a valve, uncovers them.

The delivery takes place through a port 11 provided in the pump body 1 and fitted with a check valve 11'. When the check valve is opened by pressure, this port establishes communication between the chamber in which the piston is moving, and the second chamber 12 from which the compressed air is discharged through a conduit 13 bored in the spindle 6.

The opening and the closing of the various ports are regulated with a certain retardation, the effects of which will be explained further on.

As a constructional detail must be mentioned the arrangement of the two flywheels 14 at the ends of the spindle 3 for the purpose of balancing and ensuring uniformity of working, the addition of water circulation jackets in the walls of the outer casing 7, in the side plates 8, the pump body 1 and the piston 2. Packing devices are provided at the desired points; they are preferably constituted by portions of rings applied, under the thrust of springs, against the walls concerned.

The different phases of working succeed one another in the following manner:

The machine during its rotation begins by producing a depression until the moment in which the piston 2 uncovers the suction orifice 10. A point will be reached at which the volume drawn in will reach its maximum; it is the moment when the piston reaches that end of its stroke which is the farthest away from the bottom of the body 1 (Figure 2, full lines). The phase of retardation at the closing of suction takes place at the beginning of the return stroke of the piston. The air drawn in is then delivered through the port 11 through its valve and then escapes through the orifice 13.

The positions of the various ports are, as already stated, offset or displaced, so as to give some retardation to their opening and to their closing, the object of this being to make possible an almost complete recuperation of the inertia or momentum of the gase-

ous mass in movement, thus obtaining a very complete cylinder-full or charge.

The retardation at the opening of the suction port has the great advantage of allowing a great part of the work of compression to be absorbed by the clearance. It thus produces at the moment of opening, a depression in the pump body which makes it possible to obtain a sharp draft of air.

10 The retardation at the closing of the suction port makes it possible to obtain a super-compression of the air in the casing at the moment of closing of the suction port.

15 It goes without saying that the constructional details given with reference to the very diagrammatic drawings, must be taken merely as examples, and that they could be varied in practice without departing from the spirit of the invention.

20 Claims:

1. A compressor comprising a casing, a pump body oscillating within the said casing, a piston reciprocating within the said pump body, means for oscillating the said pump body and reciprocating the said piston, means for introducing the operating fluid into the said casing, means whereby the said fluid passes from the casing into the pump body through the suction exerted by the piston, and means whereby the fluid is discharged from the pump body to the outside of the casing.

2. A compressor comprising a casing, a pump body oscillating within the said casing, a piston reciprocating within the said pump body, means for oscillating the said pump body and reciprocating the said piston, means for introducing the operating fluid into the said casing, a port provided in the pump body and which is covered and uncovered by the piston, whereby the said fluid passes from the casing into the pump body through the suction exerted by the piston, and a discharge opening with a check valve provided in the pump body and communicating with the outside of the casing.

3. A compressor comprising a casing, a pump body oscillating within the said casing, a piston reciprocating within the said pump body, means for oscillating the said pump body and reciprocating the said piston, means for introducing the operating fluid into the said casing, a port provided in the pump body and which is covered and uncovered with a certain retardation by the piston, whereby the said fluid passes from the casing into the pump body through the suction exerted by the piston, and a discharge opening with a check valve provided in the pump body and communicating with the outside of the casing.

4. A compressor comprising a casing, a pump body oscillating within the said casing, a piston reciprocating within the said pump body, means for oscillating the said

pump body and reciprocating the said piston, means for introducing the operating fluid into the said casing, a port provided in the pump body and which is covered and uncovered by the piston, whereby the said fluid passes from the casing into the pump body through the suction exerted by the piston, a discharge opening with a check valve provided in the pump body and communicating with the outside of the casing, and suitable packing means preventing leaks of said fluid through the motion of the pump body and the piston within the casing.

5. A compressor comprising a casing, a hollow spindle mounted into the said casing, a pump body oscillating about the said spindle within the said casing, a piston reciprocating within the said pump body, a driving spindle mounted in said casing in parallelism with the hollow spindle for effecting the reciprocating motion of the piston and the oscillating motion of the pump body, an eccentric keyed on the said driving spindle, and a cage mounted in the piston and provided with an oblong opening in which rolls the said eccentric.

6. A compressor comprising a casing, a hollow spindle mounted into the said casing, a pump body oscillating about the said spindle within the said casing, a piston reciprocating within the said pump body, means for oscillating the said pump body and reciprocating the said piston, means for introducing the operating fluid into the said casing, suction ports provided in the pump body and which are closed and opened by the piston, a hollow chamber located in the bottom of the pump body and surrounding the hollow spindle about which oscillates said pump body, a port between the said chamber and the chamber of the pump body in which reciprocates the piston, a discharge valve controlling the said port, and means whereby the fluid discharged into the said hollow chamber is evacuated through the interior of the hollow spindle.

In testimony whereof I affix my signature.
LUCIEN HAYART.
